UNITED STATES PATENT OFFICE.

JACOB LONDON, OF TUNNELTON, PENNSYLVANIA, ASSIGNOR TO SULLIVAN MACHINERY COMPANY, OF CLAREMONT, NEW HAMPSHIRE, A CORPORATION OF MASSACHUSETTS.

MINING-MACHINE AND TRUCK.

1,205,097.

Specification of Letters Patent. Patented Nov. 14, 1916.

Application filed October 1, 1914. Serial No. 864,379.

To all whom it may concern:

Be it known that I, JACOB LONDON, a citizen of the United States, and a resident of Tunnelton, county of Indiana, State of Pennsylvania, (whose post-office address is Tunnelton, Pennsylvania,) have invented an Improvement in Mining-Machines and Trucks, of which the following description, in connection with the accompanying drawings, is a specification, like characters on the drawings representing like parts.

This invention relates to mining machines being more particularly intended to provide improved means for transporting a mining machine of the self-propelled continuous cutting type from place to place and starting it into operation.

The invention will be best understood by reference to the following description when taken in connection with the accompanying illustration of one specific embodiment thereof, while its scope will be more particularly pointed out in the appended claims.

25 In the drawings: Figure 1 is a plan view of a mining machine truck embodying certain features of my invention; Fig. 2 is a side elevation of the same truck; Fig. 3 is a transverse, longitudinal section in elevation showing the swivel connection of the truck frame and taken on the line 3—3 in Fig. 2; Fig. 4 is a similar section in elevation taken on the line 4—4 in Fig. 2; Fig. 5 is a plan view of the clutch shown in Fig. 1 with a mining machine in position and about to be discharged from the truck; and Fig. 6 is an end elevation of the truck and machine as shown in Fig. 5.

Referring to the drawings and to the embodiment of the invention therein shown for illustrative purposes, in Figs. 1 to 4, inclusive, there is disclosed a form of mining machine truck on which a mining machine may be conveyed, and herein under its own power, to an appropriate position where it is called upon to perform the cutting of coal.

While the mining machine for which the truck is particularly designed may be of any suitable or appropriate type, herein it is of the general class or type disclosed in prior patent to Mitchell No. 656,414. That is to say, the mining machine is provided with a cutter bar 1 having the cutter chain 2 projecting from one end of the machine

and with the casing 3 inclosing the motor gearing and operative parts of the machine for driving the cutter chain and propelling the machine, it all being mounted upon a bottom plate or shoe 4 on which the machine 60 is adapted to slide along the mine bottom while cutting a kerf in the coal. A driving sprocket 5 driven through the transmission gearing (not shown) of the machine is adapted to engage a cable chain 6 and both 65 propel and guide the machine in making the lateral cut, as well as in making the starting or sumping cut in the manner explained in the aforesaid Mitchell patent.

While the invention is shown as applied 70 to a machine of the described type, it will be evident that as to many essential features it may be usefully employed with mining machines widely differing in constructional details and mode of operation from 75 the one hereinabove referred to.

Referring to the constructional features of the truck illustrated in Figs. 1 to 4, inclusive, the same is mounted upon two pairs of truck wheels 10 carried by axles 11, the latter journaled in the brackets 12 attached to the fixed or under portion of the truck frame. The latter is herein formed by the two longitudinal angle irons 13 and 14 connected at the front by the transverse bridging piece 15 and at the rear by the similar piece 16 to form a rigid rectangular frame. Intermediate the bridging pieces 15 and 16 the angle irons 13 and 14 are also connected by and rigidly attached to a bridging piece 85 17 which serves as a support on which the upper or swiveled portion of the truck frame may be turned. The upper portion of the truck frame is composed primarily of the longitudinal angle irons 18 and 19 95 connected by the transverse plates 20 and 21 which latter rest upon and have sliding contact with the bridging pieces 15 and 16, respectively, of the lower truck frame. Intermediate the transverse plates 20 and 21 the upper truck frame has fixedly secured thereto a circular plate or turntable 22 which is swiveled to turn upon the correspondingly shaped bearing plate 23 represented by the intermediate bridging member 17 of the 100 lower frame member, the turntable 22 having fastened thereto the hub 24 journaled in the intermediate member 17 and held in position thereon by the plate 25 clamped to the hub and to the turntable. In virtue of 110

its swiveled support upon the lower frame member the upper frame member which carries the mining machine may be turned to present its longitudinal axis of alignment with that of the lower frame member or at right angles thereto or at any intermediate position.

The mining machine as indicated in Figs. 5 and 6 when loaded on a truck is adapted to rest upon the angle irons 18 and 19, but may be discharged from the truck at any desired angular position with relation thereto, being guided in a right line direction in its discharge movement by the upright sides 15 of the angle irons between which the frame and shoe of the machine is adapted to slide and be guided. The forward or discharge end of the swivel frame is preferably provided with flared ends 26 and 27, respectively, formed by flaring out the angle irons 18 and 19 and these ends preferably project beyond the stationary truck frame.

The stationary or lower frame of the truck is herein shown provided with supporting devices located at the rear of the machine whereby the truck may be propelled under the power of the machine and also for supporting an electric cable reel. For this purpose the angle irons 13 and 14 have 25 secured thereto rearwardly and upwardly extending prolongations 28 and 29 connected by the cross plate 30 and carrying the supporting arms 31 and 32 for supporting a cable rail. To propel the truck there is 30 also provided on the frame formed by the rearwardly extending members 28 and 29 a truck driving gear 33 journaled about an upright axis and adapted to drive the truck through appropriate connections. For this 35 purpose the gear 33 turns the beveled gear 34, the latter meshing with the gear 35 and the latter in turn drives the transverse shaft 36 through the beveled gears 37 and 38. At the side of the truck the shaft 30 40 is provided with a sprocket wheel 37* which turns the rear axle of the truck through the sprocket chain 38* and sprocket wheel 39. The forward truck axle is driven from the rear axle by means of the connecting 45 sprocket chain 40. The truck driving gear 33 is so disposed upon the frame that when the mining machine is loaded on the frame and in its rearmost position it is caused to mesh with the truck driving pinion 41 carried by the machine and driven from the 50 motor on the machine through appropriate transmission devices (not shown). The truck wheels 10 are adapted to travel upon a suitable trackway 42 laid upon the bottom 55 of the mine.

With the described form of truck the mining machine after having been loaded on to the truck with the upper frame in alignment with the lower frame, *i. e.* lengthwise 60 of the trackway, may be propelled under the

power of the mining machine to the room or other location in the mine where the cutting is to be performed. When the desired position is reached, the upper frame may be turned about its swiveled support to discharge the machine laterally at any required angle. The machine is particularly adapted for bench work where the cut is to be made upon a bench already formed. When brought to the side of a bench such 70 as is indicated at 43 in Figs. 5 and 6 and properly angled the sumping or starting cut upon the bench may be commenced directly from the truck itself by suitably fixing or anchoring the forward end of the guiding 75 and feeding chain 6 as is indicated in Fig. 5. The truck, therefore, not only serves a function as a conveying device for the machine, but also acts as a starting frame which may be angled as required and from 80 which the machine may be discharged at a height suitable for immediately commencing the starting cut on the bench. In bench work, therefore, the truck eliminates all the preliminary setting up of the machine by 85 making it possible to start the cut at the required angle and at the required height directly from the truck, thereby saving a large percentage of the time required.

While I have herein described and illustrated one specific form of the invention, it will be understood that application of the same, other than the one herein shown may be made and that extensive deviations may be had without departing from the spirit of 90 the invention.

Claims:

1. In a mining machine truck, the combination with truck wheels, a lower frame, an upper frame swiveled on the lower frame, and guiding means carried by the upper frame for guiding a mining machine in its discharge from the truck in the direction in which the upper frame is angled.

2. In a mining machine truck, the combination with truck wheels, a lower frame, a machine guiding frame swiveled on said lower frame, and guide rails carried at the sides of said guiding frame for guiding a mining machine during its discharge from the truck in the direction in which the guiding frame is angled.

3. In a mining machine truck, the combination with truck wheels, a lower frame, a machine guiding frame swiveled on said lower frame, and means carried by said guiding frame for directing a mining machine longitudinally thereof and subsequently enabling an angular movement of said machine.

4. The combination with a mining machine of the continuous cutting type and having means on which the machine is adapted to be propelled along the mine bottom, of a mining machine truck and a swiv- 130

- eled starting frame on said truck from which said machine is adapted to be discharged.
5. In a mining machine, truck wheels, a lower frame supported thereon, a machine guiding frame normally disposed longitudinally of said lower frame and swiveled thereon for angular movement, and a mining machine movable longitudinally of said 10 guiding frame and supported thereby during the unloading operation.
6. In a mining machine truck, truck wheels, a lower frame supported thereon, a machine guided frame swiveled on said 15 lower frame, a mining machine supported by said wheels and movable longitudinally of said guiding frame, and means for moving the same longitudinally of said guiding frame onto the floor.
- 20 7. In a mining machine truck, truck wheels, a lower frame carried thereon, a machine guiding frame swiveled on said lower frame, a mining machine supported by said wheels and movable longitudinally 25 of said guiding frame, and means for driving said wheels from said machine in one position of the latter.
8. In a mining machine truck, truck wheels, a fixed lower frame carried thereon, 30 truck driving mechanism at one end of said frame connected to said wheels, a machine guiding frame swiveled on said lower frame, a mining machine movable longitudinally of said swiveled frame, and coöperating truck 35 driving means on said mining machine.
9. In a mining machine truck, truck wheels, a lower frame carried thereon, a machine guiding frame swiveled on said lower frame, a mining machine supported by said 40 wheels and movable longitudinally of said guiding frame, means for driving said wheels from said machine, and means for moving said machine longitudinally of said guiding frame.
- 45 10. The combination with a mining machine of the continuous cutting type and having means on which the machine is adapted to be propelled along the mine
- bottom, of a mining machine truck, propelling means on said truck adapted to engage with suitable driving mechanism on the machine and a machine receiving frame adapted to be angled with relation to the truck, to discharge the mining machine therefrom.
- 50 55
11. The combination with a mining machine of the continuous cutting type and having means on which the machine is adapted to be propelled along the mine bottom, of a mining machine truck and means on said truck whereby the machine may move during the starting cut directly from the truck in a direction transverse to the longitudinal axis of said truck.
- 60 65
12. The combination with a mining machine of the continuous cutting type and having means on which the machine is adapted to be propelled along the mine bottom, of a mining machine truck carrying a pivoted starting frame providing means for 70 guiding said machine on a starting cut transverse to the longitudinal axis of said truck.
- 75 80
13. The combination with a mining machine of the continuous cutting type and having means on which the machine is adapted to be propelled along the mine bottom, of a pivoted starting frame providing means for guiding said machine on a starting cut transverse to the longitudinal axis of said truck.
- 85 90
14. The combination with a mining machine of the continuous cutting type and having means on which the machine is adapted to be propelled along the mine bottom, of an elevated starting frame for guiding and starting the sumping cut at an elevation above the bottom on which the starting frame rests.
- In testimony whereof, I have signed my name to this specification, in the presence of two subscribing witnesses.
